UNITED STATES PATENT OFFICE.

JOSEPH WISNIEWSKI, OF NEW ACME, WYOMING.

ROTARY PUMP.

1,319,446.

Specification of Letters Patent.

Patented Oct. 21, 1919.

Application filed January 30, 1919. Serial No. 274,094.

To all whom it may concern:

Be it known that I, JOSEPH WISNIEWSKI, a citizen of Poland, residing at New Acme, in the county of Sheridan and State of Wyoming, have invented certain new and useful Improvements in Rotary Pumps, of which the following is a specification.

The invention provides a pump which is automatic in operation and designed for use 10 in connection with a flowing stream to be operated by the current for elevating a portion of the water and delivering the same at the required point of use.

The invention provides a pump embodying 15 a stator and a rotor, the stator comprising a cylinder or casing and the rotor embodying a piston arranged to operate in the annular space of the stator and provided with blades which receive the force of the 20 flowing water and impart movement through the rotor.

The drawings illustrate a preferred embodiment of the invention, however, it is to be understood that in adapting the same to 25 meet different conditions, various changes in the form, proportion, and minor details of construction may be resorted to without departing from the nature of the invention as claimed hereinafter.

30 In the accompanying drawings:—

Figure 1 is a top plan view of a rotary pump embodying the invention.

Fig. 2 is a side view thereof.

35 Fig. 3 is a view of the pump as seen from the underside.

Fig. 4 is a sectional detail on the line 4—4 of Fig. 1 looking to the left as indicated by the arrow.

40 Fig. 5 is a sectional detail on the line 5—5 of Fig. 10.

Fig. 6 is a horizontal section on the line 6—6 of Fig. 5.

Fig. 7 is a vertical transverse section on the line 7—7 of Fig. 5.

45 Fig. 8 is a sectional detail on the line 8—8 of Fig. 4.

Fig. 9 is a sectional detail of a modified

form of stator showing the portion of the rotor in position.

Fig. 10 is a detail view of a portion of the 50 stator showing the piston of the rotor.

Fig. 11 is a sectional detail on the line 11—11 of Fig. 10.

Corresponding and like parts are referred to in the following description and indicated in the several views of the drawings 55 by like reference characters.

The rotor and the stator are of annular form and may be of any desired construction within the purview of the invention. 60 The stator comprises similar or complementary parts 1 and 2 which are of annular formation and have their middle portions outwardly deflected to form an annular space 3 which constitutes the cylinder or 65 casing of the pump. The parts 1 and 2 are adapted to be connected in any manner by suitable fastenings 4. The flanges or edge portions of the members 1 and 2 at one side of the annular space 3 are spaced apart 70 and their opposing faces are formed with matching grooves 5 to receive an enlarged portion 6 of the rotor. A bar or supporting member 7 is secured to the stator and serves as means for securing the pump in the required position. Keepers 8 are secured to the bar or supporting member 7 and are adapted to receive poles or beams 9 by means 75 of which the pump is retained in place in the stream or other flowing water. The poles or beams 9 may be anchored in the banks of the creek or stream to retain the pump in position. A vertical shaft 10 is mounted in the bar or supporting member 7 and carries the rotor.

80 The rotor comprises an annular member of angle formation in cross section and comprising two wings 11 and 12, the wing 11 being disposed to occupy a vertical position and the wing 12 a horizontal position. The 85 vertical wing 11 is formed with the enlargement 6 which fits snugly within the space formed by the matching grooves 5. The vertical wing 11 of the rotor comes between

the spaced edge portions of the parts 1 and 2. The blades 13 are hingedly connected to the rotor as indicated at 14. The hinged connections 14 may be of any type to admit 5 of the blades having a feathering movement so as to present a maximum surface to receive the action of the flowing water and a minimum surface to the resistance of the current. Stops 15 carried by the blades 14 are 10 adapted to hold said blades in position to receive the full force of the flowing water so as to impart a rotary movement to the rotor. A piston 16 carried by the rotor is disposed to operate in the annular space or 15 cylinder 3 of the stator. The shaft 10 is provided with a hub 17 in which the inner ends of the blades 13 are journaled.

At a suitable point in its circumferential length the stator is provided with a chamber 20 18 which opens into the cylinder, the annular space 3 and from which extends a discharge pipe 19. At one side of the chamber 18 the stator is provided with a plurality of inlets 20 for the entrance of water 25 into the cylinder or annular space 3. A gate 21 is disposed between the inlet 20 and the outlet 19 and is movable across the cylinder or annular space 3. The gate 21 is mounted in a casing 22 which constitutes a portion 30 of the chamber 18. The gate 21 is normally held closed by means of contractile springs 23 which are attached to lateral extensions at the upper end of the gate and to projections of the casing. A lever 24 mounted between 35 its ends is connected at one end to the gate 21 and its opposite end is free and adapted to be engaged by means of a lever 25 mounted upon the stator and having one end projecting into the path of a trip 26 carried by 40 the rotor. As shown most clearly in Fig. 1 the lever 25 has a lateral extension 27 which is notched to receive the lever 24. A spring 28 co-operates with the lever 25 to hold it in a given position that is, with its 45 lower end in the path of the trip 26.

In the operation of the invention the pump is disposed in a stream or current of water and is made secure in any manner as by means of the parts 9. The flowing water 50 acting upon the blades 13 imparts a rotary movement to the rotor which causes the piston 16 to travel in the cylinder or annular space 3. It is assumed that the piston 16 has just passed the gate 21 and the latter is closed. As the piston travels in the cylinder 3 it draws water into the cylinder 3 through the inlets 20 and when the rotor makes a complete revolution and just prior to reaching the gate 21 the trip 26 actuates 55 the lever 25 which in turn operates the lever 24 and elevates the gate to admit of the piston passing thereby. The cylinder is now 60 filled with water and during the next revolution of the rotor the water previously drawn

into the cylinder or annular space 3 is sub- 65 jected to a compressive force and is expelled from the cylinder through the chamber 18 and discharge pipe 19 and delivered at the required point of use. During the 70 second revolution of the rotor water is drawn into the cylinder at the same time that the water previously drawn therein is discharged. After the pump has started, its 75 operation is continuous since it simultaneously draws in a supply of water and discharges water as will be readily understood. As indicated in Figs. 7 and 9 rings 29 are 80 fitted into the spaced portions of the members 1 and 2 and secured therein by suitable fastenings 30. This makes provision for ready removal or insertion of the rotor without requiring the separation of the parts 1 and 2. This is of advantage as it admits of 85 the rotor being removed and replaced without disturbing the stator when the pump is in position.

The foregoing description and the drawings have reference to what may be considered the preferred, or approved, form of my invention. It is to be understood that I may 90 make such changes in construction and arrangement and combination of parts, materials, dimensions, et cetera, as may prove expedient and fall within the scope of the appended claims.

Having thus fully described my invention, what I claim as new and desire to secure by Letters Patent is:—

1. A rotary pump, comprising a stator embodying complementary inner and outer 100 annular members having intermediate portions oppositely deflected to form a cylinder and having portions at one side of the cylinder spaced apart, an annular rotor having a portion filling the space at one side 105 of the cylinder, a piston carried by the rotor and operable in the cylinder and blades connected with the rotor.

2. A rotary pump, comprising a stator embodying inner and outer annular members having intermediate portions oppositely deflected to form a cylinder and having portions at one side of the cylinder spaced apart 110 and formed in their faces with matching grooves, an annular rotor having a portion entering and filling the said space and enlarged at its sides to enter the said grooves and retain the rotor in position, a piston carried by the rotor and operable in the cylinder and blades connected with the 115 rotor.

3. A rotary pump, comprising a stator embodying a cylinder having an inlet and an outlet, a gate operable across the cylinder and disposed between the inlet and outlet, a rotor, blades connected with the rotor, a piston carried by the rotor and operable 120 in the cylinder, a lever mounted upon the

stator and connected with the gate, a second lever mounted upon the stator and having an end portion in coöperative relation with the first mentioned lever and a trip 5 carried by the rotor and adapted to operate the second lever to cause the gate to be withdrawn from the path of the piston when the latter is passing thereby.

In testimony whereof I affix my signature in presence of two witnesses.

JOSEPH WISNIEWSKI.
